UNITED STATES PATENT OFFICE.

MICHAEL J. McLAUGHLIN, OF ST. LOUIS, MISSOURI.

ORNAMENTAL PLAQUE AND METHOD OF MAKING THE SAME.

1,272,484.

Specification of Letters Patent.

Patented July 16, 1918.

Application filed March 28, 1916. Serial No. 87,263.

To all whom it may concern:

Be it known that I, MICHAEL J. McLAUGHLIN, a citizen of the United States, residing at St. Louis, in the State of Missouri, have 5 invented certain new and useful Improvements in Ornamental Plaques and Methods of Making the Same, of which the following is a specification.

An object of my invention is to provide 10 an ornamental plaque consisting of a transparent sheet or plate having a printed or other picture or design faced thereagainst and backed up by a cast material which not only fills in the plaque to give the proper 15 strength and thickness thereto, but also forms a filler to make a background for the pictorial representation or design, should the same be of a size smaller than the dimensions of the glass or other transparent sheet 20 or plate, or should the design present cut out portions.

A further object lies in constructing the plaque in such a manner that the pictorial representation or design is hermetically 25 sealed between the transparent sheet or plate and the cast backing and filling material, and in the provision of a covering for the edges of the transparent sheet or plate and the filling material which will exclude air 30 and moisture from finding its way between the two layers of the plaque, thus making a plaque which will have a comparatively long life without deterioration.

A still further object is to provide a process 35 by which ornamental plaques may be artistically and expeditiously produced with the results as above set forth.

With these and other objects in view, my invention consists in certain novel features 40 of construction and combination of parts which will be hereinafter set forth in connection with the drawings and then more particularly pointed out in the claims.

In the drawings:—

45 Figure 1 is a view in elevation of a plaque constructed in accordance with my invention.

Fig. 2 is a transverse sectional view taken through a mold having a plaque therein.

50 Fig. 3 is a fragmentary sectional view similar to Fig. 2 showing a modified form which the invention might take.

Fig. 4 is a fragmentary sectional view taken through the edge of a plaque constructed in 55 a manner slightly different from the disclosure in Figs. 1 and 2.

As is here shown, the plaque comprises the transparent sheet or plate 1 which is preferably glass, having a pictorial representation or design printed or otherwise shown on the sheet 2, placed thereon, and a backing material 3, which is hereinafter described as plaster of Paris is cast or otherwise placed over the sheet 1 to back up the same and to fill in any cut out portions or spaces which may be left in the design.

As is shown in Fig. 2, a mold 4, partaking of a form of a pan has a recess or rim depression 5 in the bottom adjacent the side wall and by placing the transparent sheet 6 or plate upon the bottom and casting the backing material 3 in the mold, a molded rim 6 is provided around the plaque which establishes a hermetical sealing between the sheet 1 and the backing material. 75

In the disclosure in Fig. 3, the sheet 6' is shown as placed directly on the bottom of the mold 7 and the backing material 8 is cast in the mold to form a backing for the sheet 6' and to fill in any cut out or vacant 80 spaces of the sheet to bring the entire surface level with the front surface of the sheet 6'.

With the form of the structure as shown in Fig. 4, the transparent sheet or plate 9 has the printed sheet 10 placed face down thereon and with this sheet or plate 9 laid substantially level the backing material 11 is poured or cast thereon, this form of the device presenting the open edge or seam between the transparent plate 9 and the backing material 11. To hermetically seal this seam between the two materials, a layer of material or a coating of paint or other material of a somewhat thick consistency is applied as indicated at 12 around the edges 90 of the sheet or plate 9 and the backing material 11, and in this way the seam between these respective layers is sealed to prevent access of air or moisture. 100

In accomplishing the manufacture of plaques as set forth above, where molds are employed, it is preferable that the pans or molds be of the so-called enameled metal ware, these molds being either made special 105 or procured as stock pans now on the market. The picture or design, which is preferably printed or otherwise shown on a sheet of paper is then cut out so that only those portions which are desired to appear in the finished plaque remain, and this sheet is then moistened and placed face down, after which 110

the sheet is smoothed out with the hands or by the use of a damp sponge or rag in order to remove all air bubbles that may form between the sheet and the surface on which it is placed. The plaster of Paris or other backing material is then mixed to the proper consistency to flow freely before setting; the proper mixture in the use of plaster of Paris being about equal quantities of the dry plaster and of water, and this freely flowing mixture is then cast over the sheet. It will of course be understood that care must be exercised to be sure that the plaster or other backing material is of substantially equal thickness throughout all parts of the plaque, and then when the plaster has been applied to the proper depth, the cord, tape, or other hanger material 13 may be embedded in the plaster so that as the plaster hardens or sets, this hanger will be secured in place, and then when the plaque has remained for a sufficient length of time that the plaster of Paris or other backing material has set thoroughly, the plaque may be removed from the mold and the hanger 13 may be used to suspend the same from the wall.

In constructing the hermetically sealed plaque as is shown in Fig. 2, the transparent sheet or plate 1 is made of a size to fit within the mold in a relation that the edges thereof are slightly separated from the edges or side walls of the mold, thus leaving the rim depression 5 uncovered. The sheet bearing the design or pictorial representation is prepared as above set forth and after being moistened is placed on the sheet or plate 1, this sheet 2 being smoothed down by the use of the hands or by the use of a wet or moist sponge or rag. The plaster of Paris or other backing material is mixed to be of the proper consistency and is then poured into the mold 4 to the proper depth, and by reason of the fact that this backing material is in a semi-fluid state and flows freely, the backing material will find its way into the rim depression 5 and will rise up along the edge of the sheet or plate 1, at the same time filling in over the sheet 2, and in this way a hermetically sealed joint is provided between the sheet 1 and the backing material 3.

The process used in accomplishing the result shown in Fig. 4 differs slightly from those hereinbefore set forth in that it is not absolutely essential that a mold be employed, and in the accomplishment of this process, the sheet or plate 9 is placed upon a support in a substantially horizontal and level relation, the sheet 10 is then moistened and placed on the upper side of the sheet 9 after which it is pressed out and smoothed as

above set forth, and the plaster backing material is then cast over the sheet 10 and on the upper side of the sheet or plate 9 by being poured, the spreading of the semi-liquid backing material causing the same to flow over the back of the sheet 9 and at the edges to run over in a gradual curve as shown. After the backing material has been applied to the proper thickness, the plaque is laid away until the backing material 11 has set properly, a paper or fabric layer is placed over the edges of the glass or other transparent sheet and the plaster or other backing material and is cemented thereto, or a layer of paint, gilt, or other material is applied to these edges as is shown at 12, the purpose of this edge covering being to fill and cover the seam between the sheet 9 and the backing material 11 at the edges thereof, so that the hermetical seal cannot be broken by the air or moisture finding its way through this seam between the transparent sheet 9 and the backing material to cause separation of the same.

While I have herein shown and described only particular forms of the finished product as accomplished, and only certain methods and processes of accomplishing this finished product have been set forth, it will be understood that modifications and variations might be made in the plaque and in the method of making the same, and hence I do not wish to be limited to the exact disclosure but only to such points as may be set forth in the claims.

I claim:-

1. An ornamental plaque comprising a transparent sheet, a sheet having a pictorial representation thereon placed against said transparent sheet, and a backing of a moldable material placed over the pictorial sheet and the transparent sheet to extend around the edges thereof.

2. The method of making hermetically sealed ornamental plaques consisting of placing pictorial representations or designs upon a transparent sheet, locating said sheet in a mold, and casting a backing material to cover over the pictorial representation or design and the back of the sheet, and at the same time to mold around the edge of the transparent sheet to establish a hermetical seal between the transparent sheet and the backing material.

In testimony whereof I affix my signature in presence of two witnesses.

MICHAEL J. McLAUGHLIN.
